UNITED STATES PATENT OFFICE.

DANIEL APPEL, OF CLEVELAND, OHIO, ASSIGNOR TO THE UNION PAPER BAG MACHINE COMPANY, OF PHILADELPHIA, PENNSYLVANIA.

PAPER-BAG-MAKING APPLIANCE.

SPECIFICATION forming part of Letters Patent No. 700,467, dated May 20, 1902.

Application filed January 13, 1902. Serial No. 89,429. (No model.)

To all whom it may concern:

Be it known that I, DANIEL APPEL, a citizen of the United States, residing at Cleveland, Cuyahoga county, Ohio, (post-office address No. 62 Holyoke Place, Cleveland, Ohio,) have invented certain new and useful Improvements in Paper-Bag-Making Appliances, (Case C,) of which the following is a specification.

This invention pertains to an appliance for use in connection with the manufacture of paper bags from a plicated paper tube; and the invention will be readily understood from the following description, taken in connection with the accompanying drawings, in which—

Figure 1 is a perspective view of an appliance exemplifying my invention; Figs. 2 and 3, the latter to be viewed as a continuation at the right-hand end of the former, a perspective view of a plicated paper tube in various stages of progress in being formed into a paper bag by the aid of my appliance; Fig. 4, a perspective view of the complete bag in condition for the market; Fig. 5, a perspective view of the bag opened out for use, and Fig. 6 a perspective view designed to serve in demonstrating more clearly and on a larger scale some of the main steps of progress in using my appliance.

My appliance is designed to deal with a plicated paper tube with ordinary bellows folds at its sides. In the drawings, 1 indicates such a plicated tube while in flattened condition; 2, oppositely-disposed transverse cuts through all of the plies of the tube, but extending inwardly a distance less than that of the inward projection of the inner plies, these transverse cuts being at the point where the mouth of a plicated bag is to be ultimately severed from the bottom end of the next bag to be completed; 3, longitudinal cuts extending through the upper and lower face-plies only of the tube, their forward extremities joining the inner extremities of the transverse cuts 2; 4, a station-point a bag-section of length in advance of the cuts 2, this station-point representing a tube condition where the cuts before referred to have been produced and then the tube opened up to its full depth, the tube having a tapering enlarge-

ment to this station-point from the earlier point, where it is in flat condition; 5, another station-point in the tube a section length still farther in advance, the tube still being in expanded condition, but vertical cut 6 at the sides in extension of the cuts 2, previously referred to, having completed the severance at the sides of the tube and a stripe of paste 7 having been applied just rearward of the transverse cuts and extending transversely across the two sides and the upper face-ply of the tube; 8, another station-point in the tube a section length still farther in advance, at which point the forwardly-presenting end portions of the sides of the tube have been folded squarely inward, as at 9, to form the under plies of the future bottom of the bag, the two face-plies still uniting the bottom of the section to the mouth of the section ahead; 10, another station-point on the tube a section length still farther in advance, at which point the bottom end of the section previously gotten into the condition indicated at station 8 has been somewhat collapsed, the infolded portions of the bottom taking a rearward bellows fold, as at 11, the tube having a vertical contraction tapering from station-point 8 and continuing forward beyond the station-point now under consideration; 12, another station-point on the tube a section length still farther in advance, where the tapering contraction of the tube has brought it to almost a collapsed condition, but not sufficiently so to bring into contact the pasted surfaces of the infolded bottom portions, the general portions of the tube thereafter remaining in collapsed condition; 13, a still farther advanced station-point, where the section in advance of the station has been retracted somewhat, thus causing the bottom members to begin to flex upwardly and downwardly, these parts approaching a plane at right angles to the general plane of the collapsed tube; 14, a station still farther in advance, at which point the section ahead of the station has been completely severed from the section to the rear of it and the previously-infolded bottom members brought into a common plane and the severed flaps folded and pasted against them to form the complete double bottom of the bag; 15, the com-

pleted bag which has been severed from the tube and has had its completed bottom folded flat down upon the tube and pressed, and 16 the completed bag when opened out ready 5 for use.

My improved appliance is designed to facilitate the carrying out of the above-described program and will be found efficient in connection with either hand or machine 10 operations upon the tube.

Attention is now called to Fig. 6, which is a demonstrative figure designed to bring out certain conditions which cannot be clearly exhibited while the tube-sections remain 15 severed. It is to be observed that before the bottom members 9 are folded inward the inside of the tube is unobstructed for its full width, but that after these members are folded inward they largely obstruct the tube, 20 leaving clear, however, a vertical slot bounded on its sides by the inner extremities of the bottom members 9 and on its ends by the upper and lower face-plies of the tube. If the infolded bottom members 9 are so proportioned 25 as to meet or lap, then even this slot will not be present; but it will be observed that there will be a thin passage-way over the lower face-plies of the tube below the horizontal portions of the inturned bottom members, this 30 passage having a width equal to the distance between the longitudinal cuts 3, heretofore referred to, there being a similar passage just below the upper face-plies of the tube. To put it in other words, while the tube is in the conditions 35 indicated at station 5 in Fig. 2 its interior is entirely unobstructed, and after it has reached the condition indicated at station 8 then disregarding the vertical slot, which may or may not be present, there would only be 40 space for the passage past the station of a thin blade at the floor of the tube and another at the ceiling of the tube, the blades having a width not greater than the distance between the longitudinal cuts in the face-plies. Now turning to the appliance 45 illustrated in Fig. 1, which takes on the form of a big mandrel over which the tube passes, 17 indicates a pair of thin blades lying one above the other and having a width equal to that 50 of the plicated tube to be dealt with, these blades being separated from each other such distance as will readily permit the passage of the inner bellows folds of the tube, the form of this portion of the mandrel being such 55 as to accommodate the tube in its collapsed condition; 18, transverse slots or notches in this portion of the mandrel, of use in facilitating the cutting of the transverse slits 2 through all of the plies of the tube; 19, a forward-tapering diverging prolongation of the two blades; 20, the forward extremity of this prolongation, at which point the distance between the two blades is equal to the height of the completely-opened tube, the trans- 60 verse dimensions at this point therefore representing the transverse dimensions of the

fully-opened tube; 21, forward-tapering converging prolongations of the tube-blades, this portion of the blades having a width about or not greater than that between the 70 longitudinal cuts 3 of the tube; 22, the forward extremity of the narrow portion of the mandrel, the blades at this point being such distance from each other as to accommodate at least two thicknesses of the paper of the 75 tube, and 23 a portion of the narrow blade parts just forward of extremity 20 of the wide part of the blades, this portion of the narrow part of the blades not partaking of the tapering convergence characterizing the 80 balance of the narrow part of the blades, but, on the other hand, maintaining the full distance apart corresponding with the height of the opened tube. If a collapsed tube be fed from the left over the mandrel, it may 85 have the transverse cuts 2 readily produced at the notches 18 of the mandrel, and the longitudinal cuts 3, extending through only the face-plies can be produced without any special provision. If the tube be then pulled 90 forward on the mandrel, it will be expanded, as at station-point 4 in Fig. 2, and the completing side cuts thus may be produced at the sides and the paste 7 may be applied, producing the condition indicated at station- 95 point 5. If now the tube be drawn forward upon the mandrel till the proper point for the infolding of the sides comes to the forward extremity 20 of the wide blades, then the ends of the tube sides may be folded inward 100 to produce the condition indicated at station-point 8 in Fig. 2. The unconverging portion 23 of the narrow blades keeps the face-plies fully separated and permits the bottom members 9 to be properly folded inwardly. This 105 operation brings portions of the infolded bottom members between the narrow blades, so that those blades occupy positions in the thin passages heretofore referred to as existing between the face-plies and the contiguous 110 infolded bottom members. If the tube be now pulled farther along the mandrel, it and its bottom folds will become collapsed, first as indicated at station-point 10 and then as indicated at station-point 12. By retracting 115 the foremost section relative to the section following the bottom members may be expanded, as indicated at station-point 13, and when the tube-point in this condition reaches the extremity 22 of the mandrel then the bag- 120 section in advance may be severed and the bottom formation may be completed, as indicated at station-point 14, and then the bottom may be folded flat and pressed as it leaves the mandrel, as indicated on the completed 125 bag at 15, the bag thus completed being severed from the section following when the bottom work of the latter section reaches the extremity of the mandrel.

It is manifest that the operations described 130 may be performed, in conjunction with the mandrel, manually when by the aid of simple

mechanism disposed at various points along and coöperating with the mandrel. The mandrel well lends itself to employment in connection with an ordinary tuber to receive the 5 plicated tube directly from the tuber, the initial portion of the mandrel forming, if desired, the usual former of the tuber and finding its support by exterior devices connecting with it through the still open seam of the 10 tube.

I claim as my invention—

1. In a paper-bag-making appliance, a mandrel comprising a pair of thin blades disposed contiguous to each other at one portion and 15 thence having a tapering divergence, the width of the blades being equal to that of the plicated tube to be dealt with, and the greatest distance between the blades being in correspondence with the fully-open condition of 20 the tube, said blades having narrowed prolongations from their point of greatest divergence, and said narrowed prolongations hav-

ing a tapering convergence, substantially as set forth.

2. In a paper-bag-making appliance, a mandrel comprising a pair of thin blades disposed contiguous to each other at one portion and thence having a tapering divergence, the width of the blades being equal to that of the plicated tube to be dealt with, and the greatest 25 distance between the blades being in correspondence with the fully-open condition of the tube, said blades having narrowed prolongations from their point of greatest divergence, and said narrowed prolongations having 30 a tapering convergence, the convergence of said narrowed prolongations beginning at a point some distance forward of the junction between the wide and narrow portions of the blades, substantially as set forth.
